[57] CLAIM

The ornamental design of a hanging ornament or the like, substantially as shown and described.

DESCRIPTION

FIG. 1 is a front elevation view of the hanging ornament or the like showing our new design;

FIG. 2 is a rear elevation view of the hanging ornament or the like shown in FIG. 1;

FIG. 3 is a right side elevation view of the hanging ornament or the like shown in FIGS. 1 and 2;

FIG. 4 is a left side elevation view of the hanging ornament or the like shown in FIGS. 1 and 2;

FIG. 5 is a top plan view of the hanging ornament or the like shown in FIGS. 1 and 2;

FIG. 6 is a bottom plan view of the hanging ornament or the like shown in FIGS. 1 and 2.

The granular filling is shown only partially for convenience of illustration.
